CLAIM

The ornamental design for a tube securing device clamp opening tool, as shown and described.

DESCRIPTION

FIG. 1 is a front perspective view of a tube securing device clamp opening tool according to the present design;

FIG. 2 is a bottom perspective view of the tube securing device clamp opening tool of FIG. 1;

FIG. 3 is a right side view of the tube securing device clamp opening tool of FIG. 1;

FIG. 4 is a front view of the tube securing device clamp opening tool of FIG. 1;

FIG. 5 is a left side view of the tube securing device clamp opening tool of FIG. 1;

FIG. 6 is a rear view of the tube securing device clamp opening tool of FIG. 1;

FIG. 7 is a top view of the tube securing device clamp opening tool of FIG. 1;

FIG. 8 is a bottom view of the tube securing device clamp opening tool of FIG. 1;

FIG. 9 is a cross-sectional view of FIG. 4 at cut line 9—9; and,

FIG. 10 is a cross-sectional view of FIG. 3 at cut line 10—10.

The broken lines depict portions of the tube securing device clamp opening tool in which the design is embodied that are not considered part of the claimed design.
